UNITED STATES PATENT OFFICE.

ROBERT SANFORD RILEY, OF WORCESTER, MASSACHUSETTS, ASSIGNOR TO SANFORD RILEY STOKER CO., OF WORCESTER, MASSACHUSETTS, A CORPORATION OF MASSACHUSETTS.

UNDERFEED STOKER.

Application filed August 4, 1919. Serial No. 315,165.

To all whom it may concern:

Be it known that I, ROBERT SANFORD RILEY, a citizen of the United States, residing at Worcester, in the county of Worcester 5 and State of Massachusetts, have invented a new and useful Underfeed Stoker, of which the following is a specification.

This invention relates to an underfeed stoker of the type in which refuse is discharged at the sides of the retort. It is the general object of my present invention to improve the construction of such stokers to the end that more efficient operation may be attained.

With this general object in view, one feature of my invention consists in providing an underfeed stoker of this general type with over-feed grates at each side of the retort which are divided along the retort into a plurality of relatively short sections, and in further providing means to oppositely reciprocate alternate sections, thus thoroughly agitating the fuel bed.

Another feature of my invention consists in the provision of a retort having side walls capable of transverse reciprocation throughout the greater portion of their height. Other features of my invention relate to the provision of improved operating devices for the movable side walls and over-feed grates, and also to certain constructions, arrangements, and combinations of parts which will be hereinafter described and more particularly pointed out in the appended claims.

Three forms of my invention are shown in the drawings in which

Fig. 1 is a front elevation of one form of my improved stoker;

Fig. 2 is a partial diagrammatic plan view thereof;

Fig. 2^a is a diagrammatic detail plan view of a modification;

Fig. 3 is a longitudinal sectional elevation 45 of the parts shown in Fig. 1;

Fig. 4 is a transverse sectional elevation, taken along the line 4—4 of Figs. 2 and 3;

Fig. 5 is a detail longitudinal sectional elevation taken along the line 5—5 in Fig. 4;

Fig. 6 is a partial transverse sectional elevation of a second form of my invention;

Fig. 7 is a horizontal section taken on the line 7—7 in Fig. 6;

Fig. 8 is a transverse sectional elevation,

similar to Fig. 4, and showing an additional 55 modification;

Fig. 9 is a side elevation of a frame member;

Fig. 10 is a detail sectional elevation taken along the line 10—10 in Fig. 3; and 60

Fig. 11 is a detailed elevation of parts of the mechanism shown in Fig. 8.

Referring particularly to Figs. 3 and 4, my improved stoker as shown therein comprises a hopper 10 from which coal is fed intermittently by a plunger or ram 11 to a trough or retort having side walls 12 and 13, and a bottom plate 14. As coal is fed to the retort by the plunger 11, the fuel body in the retort gradually increases until it 70 overflows the retort on each side thereof, being then deposited upon over-feed grates 15 and 16, disposed along the sides of the retort. The fuel gradually works down along the inclined surfaces of the grates 15 and 16, during which movement combustion is substantially completed. The ash and refuse are deposited on dumping or discharge plates 17 and 18 which extend nearly to the side walls 19 and 20. Sufficient openings 80 may be left however, between the plates 17 and 18 and the side walls to permit the refuse to drop through into the ash pit continuously.

The plates 17 and 18 are supported by 85 rack bars 21, which may be moved toward or from the side walls by manually operated pinions 22, thus adjusting the width of the discharge openings as desired.

The plate 14 forming the bottom of the 90 retort is provided with a flange or lug 23 at its front end by which it is connected to the plunger 11, being consequently reciprocated therewith. The plate 14 is also preferably provided with a plurality of upward- 95 projecting portions 24, adapted to engage the fuel and move it longitudinally of the retort. A fixed cover plate 25 may be provided at the rear end of the retort to prevent coal from being deposited behind the 100 rear of the plate 14 as the plate is drawn forward.

The plate is supported for forward and rearward movement on fixed transverse frame members 26 (Fig. 9) to which are secured guides 27 and 28 extending along each side of the plate 14. Additional cover plates 29 protect the longitudinal edges of the plate

14 and prevent coal from entering between the plate 14 and the guides 27 and 28.

The side walls and over-feed grates are formed in relatively short sections arranged longitudinally of the retort, as clearly shown in Figs. 2 and 3. Each section consists of a hollow casting or frame work 30, to the outer end of which a dumping plate 17 or 18 is pivoted at 31. The over-feed grates 15 and 16 are detachably mounted on the frames 30 as is also a casting 32, forming the upper part of both the side wall and the over-feed grate. These members 32 may be connected to the frames 30 by bolts or pins 33 extending through openings formed in corresponding lugs on the parts 30 and 32.

The hollow frames 30 are mounted to slide upon T-shaped bars 34 (Fig. 5) forming intermediate parts of the transverse frame members 26. The ends of the members 26 are widened and rest on fixed I-beams 35 (Fig. 4) or on other suitable supports. Depending projections or brackets 36 are secured to or formed integral with the frames 30 and extend below the central retort for engagement with the operating mechanism to be described. Each pair of opposed brackets 36 are connected by the plates 63 (Fig. 4).

I will now describe the mechanism by which the plate 14 may be reciprocated longitudinally and the side wall and grate members may be reciprocated transversely of the retort.

A cylinder 40 is mounted on the front of the stoker and contains a piston having a piston rod 41, slideable in suitable bearings across the front of the stoker. The piston and piston rod may be moved alternately in opposite directions by either air or steam pressure but my invention is not limited to movement of the rod 41 in any specific manner. A bell crank 42 is mounted upon a fixed vertical pivot 43 and is provided with a forked end 44, embracing the piston rod 41 and received between collars 45 and 46 adjustably secured on the shaft 41.

The second arm 47 of the bell crank 42 is connected by a link 48 to the plunger 11, previously described, and by this connection the plunger is alternately moved in and out beneath the hopper 10. By adjusting the collars 45 and 46 along the piston rod 41, lost motion may be provided and the stroke of the plunger may be thus reduced, or the relative position of the stroke may be changed.

A second lever 50 is mounted upon a fixed horizontal pivot 51, and is provided with a forked upper end 52, engaged between a collar 53 secured to the rod 41, and a collar 54 adjustable thereon. The lower end of the lever 50 is connected by a link 55 to an arm 56 mounted on a cam-shaft 57. The

shaft 57 extends longitudinally below the retort and is supported by suitable bearings 58, as shown in Fig. 3.

The cam-shaft is provided with two series of cams 59 and 60, which are oppositely disposed on the shaft. Each depending cam 59 engages faces 62 formed on opposed projections 36 (Fig. 4). The upwardly extending cams 60 engage upper faces 62^a (Fig. 10) on projections 36 associated with the next adjacent pair of sliding castings or frames 30.

As the piston-rod 41 is reciprocated, the arm 56 is oscillated, and in turn produces an oscillating movement of the cams 59 and 60. Such movement of the cams reciprocates successive side wall and grate sections as units alternately in opposite directions with respect to adjacent sections. This alternate movement of adjacent sections is very effective in thoroughly agitating the fuel bed.

It is usual to supply forced draft for a stoker of this kind, and for this purpose the entire space below the retort may form an air passage to the side walls of the retort, which are perforated as shown in Fig. 4 to admit air to the fuel in the retort. It is frequently desirable to admit air at reduced pressure to the fuel on the over-feed grates, and for this purpose I provide an intermediate partition 64 in each sliding member 30, such partition forming a chamber 65 below the grates, connected by openings 66 and 67 to a chamber 68. The admission of air to each chamber 68 is controlled by dampers 69, mounted on a shaft 70, and operated by a handle 71 (Fig. 1).

With this arrangement, full air pressure is delivered to the side walls of the retort, while the pressure on the over-feed grates may be reduced to any desired extent.

In Figs. 6 and 7, I have shown a second form of my invention, involving structural modifications.

In this construction, the sliding members 72 are formed as separate pieces, each provided with a depending bracket 73, which may be secured to the member 72 by bolts 74. The oppositely disposed brackets 73 of each pair are connected by a tie-plate 75 and the oscillating cam reciprocates the members 72 by engagement with the faces of the brackets 73 as previously described.

In this construction, the entire portion 76 which forms the retort side wall is detachable and replaceable as a unit, the lower end being conveniently held in position by a bolt 76^a dropped loosely into openings provided therefor, and the upper end being also suitably secured to the sliding member 72.

A loose plate 78 separates the interior of the sliding member 72 into two compartments for air distribution, and the pressure

of the air in the left hand compartment (as viewed in Fig. 6) may be controlled by a sliding damper 79. The dumping plates 80 are each provided with a split bearing 5 adapted to receive pivots 81 (Fig. 7) on the member 72 which extend toward each other and into the bearing of the plate.

This form of my invention differs only in details of construction from the form first 10 described, the operation of both being identical.

In Figs. 8 and 11 I have shown a second modification in which not only adjacent side wall sections are oppositely reciprocated but in which the two corresponding wall sections on opposite sides of the retort are also oppositely reciprocated, so that they alternately approach and recede from each other.

20 To attain this result, I provide upper and lower brackets 82 and 83, each secured to or formed integral with its associated side wall section and I provide each of these brackets with a recessed extension 84 or 25 85. These recessed extensions are positioned respectively above and below the cam shaft 57 upon which a plurality of double cams 86 are secured, cooperating with said extensions the brackets associated 30 with adjacent pairs of side wall sections are oppositely disposed, the bracket extensions for one pair being shown in Fig. 8 and for the next adjacent pair in Fig. 11.

As the shaft 57 is oscillated, the opposite 35 side wall sections approach and recede from each other and the next adjacent sections each move simultaneously but in the opposite direction. The fuel bed is even more thoroughly agitated in this form of my invention than in the forms previously 40 described, as the fuel is forced upward out of the retort by the approaching side wall sections.

In all forms of my invention, the corners 45 of the side wall sections may be rounded as at 30^a in Fig. 2^a, giving a slightly conical or plow-like effect to the inner ends of the sections, designed to assist in heaving the fuel upward and breaking up the fuel bed.

Having thus described my invention, it will be evident that changes and modifications can be made therein by those skilled in the art within the scope of my invention as set forth in the claims, and I do not wish 50 to be otherwise limited to the details herein disclosed, but what I claim is:—

1. An underfeed stoker having in combination, a retort with side walls formed in sections successively disposed along said retort, over-feed grates also formed in sections, each grate section being connected to move with an associated side wall section, and means to reciprocate adjacent side wall sections and their associated grate sections 55 simultaneously in opposite directions.

2. An underfeed stoker having, in combination, a retort with side walls formed in sections successively disposed along said retort, over-feed grates also formed in sections, each grate section being connected to move with an associated side wall section, 75 sectional discharge plates pivotally connected to said grate sections, means to reciprocate each corresponding side wall section, grate section and discharge plate section as a unit, and means to vary the path of movement of said discharge plates.

3. An underfeed stoker having, in combination, a retort with side walls formed in sections successively disposed along said retort, over-feed grates also formed in sections, each grate section being connected to move with an associated side wall section, and means to reciprocate each side wall section and its corresponding grate section 80 as a unit horizontally, adjacent units being reciprocated simultaneously in opposite directions.

4. An underfeed stoker having, in combination, a retort with side walls formed in sections successively disposed along said retort, over-feed grates also formed in sections, each grate section being connected to move with an associated side wall section, a cam shaft extending longitudinally beneath 95 said retort and having a plurality of cam portions disposed thereon, and a member carried by each combined side wall and grate section and positioned for engagement by one of said cam portions.

5. An underfeed stoker having, in combination, a retort with side walls formed in sections successively disposed along said retort, over-feed grates also formed in sections, each grate section being connected to move with an associated side wall section, discharge plates pivotally connected to said grate sections, and means to reciprocate each corresponding side wall section, grate section and discharge plate section as a unit 100 transversely of said retort to effect lateral fuel feed and ash discharge.

6. An underfeed stoker having, in combination, a longitudinal retort with movable side walls extending approximately to the 115 bottom of said retort, overfeed grates connected to move with said side walls transversely to the axis of said longitudinal retort, and means to horizontally reciprocate said side walls and associated overfeed 120 grates transversely of said retort to effect lateral distribution of fuel over said grates.

7. An underfeed stoker having, in combination, a longitudinal retort with movable side walls, overfeed grates connected to move with said side walls transversely to the axis of said longitudinal retort, ash discharge plates pivotally mounted at the outer ends of said overfeed grates, adjustable 125 means to support said plates, and means to 130

- horizontally reciprocate said side walls, said overfeed grates and said discharge plates transversely of said retort to effect lateral fuel feed and ash discharge.
- 5 8. An underfeed stoker having, in combination, a rigid frame, a plurality of supporting members mounted on said frame and extending transversely across said stoker in closely adjacent parallel relation, each
- 10 supporting member having a flat upper bearing surface with a plurality of air openings therein, retort side walls and overfeed grate sections slidably mounted on said flat supporting members and receiving air through
- 15 said openings, and means to reciprocate adjacent sections of said side walls and associated grates as units simultaneously in opposite directions with respect to adjacent sections.
- 20 9. An underfeed stoker having, in combination, a retort with side walls formed in sections successively disposed along said retort, overfeed grates also formed in sections, each grate section being connected to move
- 25 with an associated side wall section, and means to move oppositely-disposed wall sections alternately toward and away from each other, and to simultaneously move adjacent sections in the opposite directions.
- 30 10. An underfeed stoker having, in com-
- bination, a longitudinal retort with movable side walls extending approximately to the bottom of said longitudinal retort, said walls being formed in sections disposed longitudinally of said retort, overfeed grates formed in sections, each connected to move with one of said side wall sections transversely to said longitudinal retort, and means to cause oppositely disposed wall sections and the grate sections associated therewith to alternately approach and recede from each other to effect lateral fuel feed, adjacent wall sections and their associated grate sections as units moving simultaneously in opposite directions with respect to adjacent sections. 40
11. An underfeed stoker having, in combination, a retort with side walls formed in sections successively disposed along said retort, overfeed grates also formed in sections, each grate section being connected to move with an associated side wall section, and means to reciprocate adjacent side wall and grate sections as units simultaneously in opposite directions with respect to adjacent sections, the inner corners of each wall section being shaped to cause said wall section to have a wedging lifting action on the fuel. 50
- 55 In testimony whereof I have hereunto affixed my signature.

ROBERT SANFORD RILEY.
